UNITED STATES PATENT OFFICE.

JOHN BOLAND, OF DECATUR, ILLINOIS, ASSIGNOR OF ONE-HALF TO
CHARLES E. PEEBLES, OF RAYMOND, ILLINOIS.

ACETYLENE-GAS-GENERATING APPARATUS.

SPECIFICATION forming part of Letters Patent No. 608,643, dated August 9, 1898.

Application filed July 3, 1897. Serial No. 643,358. (No model.)

To all whom it may concern:

Be it known that I, JOHN BOLAND, of Decatur, in the county of Macon and State of Illinois, have invented certain new and useful 5 Improvements in Apparatus for Generating Acetylene Gas, of which the following is a specification.

This invention is designed to provide a cheap, simple, and effective generator for 10 acetylene gas which may be built by sheet-metal workers without special provision of any consequence. It is exemplified in the structure hereinafter described and it is defined in the appended claims.

15 In the drawings forming part of this specification, Figure 1 is a central vertical section through a generator embodying my improvements, showing the parts adjusted to generate gas. Fig. 2 is a plan of the generator shown 20 in Fig. 1. Fig. 3 is a central vertical section through the generator, showing the carbid raised from contact with the water by action of the gasometer. Fig. 4 is a detail in central vertical section, showing the transmission- 25 pipe leading from the generating-chamber closed by a water seal. Fig. 5 is a detail in plan of mechanism used to control the water seal and hold the generator-cover in place.

In constructing a generator in accordance 30 with my invention a gasometer-tank 1 is made of any desirable size and proportion and is supplied with a cover, as 2. At some point in the gasometer-tank an air-chamber 3 is built from the bottom upward to above the 35 water-line of the gasometer, and it is open at the bottom and closed at the top. Through the air-chamber are extended pipes, as 13 and 22, one of which leads to the generating-chamber and the other to a storage-tank or to the 40 service-pipes direct. The pipe 22 extends upward alongside the gasometer-tank, and it forms a guide for the gasometer-cover. A bracket 23 is fastened to the top of the cover. It is bored to receive pipe 22, and as the cover 45 rises and falls the bracket slides along the pipe.

A generator-tank 4 is made, preferably, of a circular outline in plan, and it has on opposite sides narrow vertical recesses 4^a and 50 4^b, communicating with or forming part of its interior. One of the vertical recesses 4^b of

the generator-tank conjoins with the gasometer-tank, as shown in Fig. 2, and through such recess extends a rod 18. The rod has a sliding bearing in a block in the upper end 55 of the recess. It extends downward to the bottom of the generator-tank and when the generator is in operative condition returns upward toward the upper end of the tank and carries the carbid-basket 19 on such upturned 60 portion. Above the sliding bearing in the recess the rod extends upward some little distance and passes through an aperture in a bracket 24, which is fastened on the top of the cover of the gasometer. 65

Above the bracket 24 a collar 25 is fastened onto the rod 18 by means of a set-screw or other suitable means permitting adjustment of the collar. The rod acts with pipe 22 to guide the gasometer-cover in its rise and fall, 70 and it is or may be acted on by the gasometer-cover in a manner to automatically raise and lower the carbid-basket. This is exemplified in Fig. 3, where the gasometer-cover has acted on the rod through the bracket 24 and the 75 collar 25 and has raised the carbid from contact with the water and suspended the formation of gas. As the gasometer-cover descends from the position shown in Fig. 3 the carbid-basket will descend through force of gravity 80 until the carbid is again immersed, when gas developed and accumulated in the gasometer may again raise the basket, and so on indefinitely. The location of the collar 25 on the rod determines the amount of gas that may 85 accumulate in the gasometer before the carbid will be raised out of contact with the water, and the location of the collar may be varied in an obvious manner to suit different circumstances or different requirements. The 90 pipe 13, which leads from the generator-tank to the gasometer-tank, rises quite a distance above the water in the generator-tank, and it has an inverted cup 14 set over such end and out of contact therewith. The means preferably employed to sustain the cup on the pipe 95 consist of a collar 16, fixed on the pipe, and a spider 15, inside the cup, which is bored to receive the pipe and adapted to rest on the collar. 100

In the vertical recess 4^a of the generator-tank is a rod 10, which extends downward

toward the bottom of the tank, then bends inward and upward, and connects at its upturned end with a float 11. The float is of annular construction, and it encircles the 5 pipe 13. On the upper end of the float is an annular can 12, the upper end of which is open below cup 14 and adapted to receive the cup. When the generator is in operative condition, the upper end of the can is submerged, 10 as shown in Fig. 1, while the lower end of cup 14 is some distance above the water, and preliminary to removing the cover of the generator-tank for the purpose of supplying carbid or for any other purpose the can is raised until the lower end of the cup is submerged in 15 its contents and a water seal, which effectively prevents passage of gas from the gasometer, is formed. The upper end of rod 10 is supplied with a rotatable button or cross-bar, as 9, and a hooked or undercut catch 8 is fastened onto the wall of recess 4^a in position to engage the button.

The cover for the generator-tank is shown at 5. Its side wall 5^a extends between the 25 members of rod 18 and between rod 10 and the float. It has a dome 6, into which the upper end of pipe 13 extends. It is supplied with a valve 17, and it has a lip 7, which is adjacent to catch 8 when the cover is in position. The lip provides a point of engagement for an end of button 9, and when the cover and the float are properly lowered the button 9 may be turned with one end under the catch and the other end above the lip, as 30 shown in Fig. 5, and both the can and the cover will be held in position by the button.

The carbid-bucket 19 is fastened to an upturned end of rod 18. It contains a reticulate basket 20 for the carbid, and it has a set 40 of perforations 21 in its side wall some distance above its bottom and below the carbid. The bottom of the bucket is imperforate to retain sediment, and the perforations 21 permit the water to contact with the carbid from 45 below when the bucket is lowered, and thereby begin the generation of gas in a preferred manner.

When it is desired to open the generating-tank to supply carbid to the basket, for instance, the rod 18 is raised until the carbid is out of the water, and fastened in that position by means of the collar 25. The button 9 is then turned free of catch 8 and the float is permitted to raise the can into sealing connection with the cup, after which the valve 17 is opened and the cover 5 is lifted from the tank. When the basket is supplied with carbid, the above-enumerated steps are performed in reverse order and the apparatus is 55 ready for operation. The float is a convenience rather than a necessity, as the rod 10 and the can thereon may be raised by hand and secured by some well-known form of catch. The float is preferred, however, on 60 account of its automatic action.

The air-chamber in the gasometer, through which pipes 13 and 22 extend, is of utility in

obviating the condensation of vapor in pipe 13. In generating gas some little vapor is formed, and if this were passed through a 70 pipe directly surrounded by water there would be a tendency to condensation, which might in time fill the lower run of pipe 13 and prevent flow of gas.

The water seal is not likely to become inoperative by accumulation of impurities or corrosion. It may be easily cleaned if it should become obstructed or corroded, and it takes the place of a more expensive valve, which would be subject to the disadvantages mentioned. The rod of the can of the water seal has such motion with relation to the water in the generator-tank that when the rod is lowered the can is entirely submerged. This makes it certain that the can will always be 85 filled and assures proper action of the water seal whenever the rod is raised.

The dome 6 rises above the cover 5 in order that the cup 14 may be raised well above the carbid, so that the fumes from the carbid 90 may settle before they reach the outlet-pipe and the gas be discharged in as dry condition as possible.

The generator-tank is entirely separated from the gasometer-tank except for passage 95 of gas. This confines the impurities developed by gas generation to the generator-tank and leaves the water in the gasometer-tank uncontaminated. The comparatively small amount of water in the generator-tank may 100 be easily renewed whenever it becomes too impure.

By utilizing the pipe 22 and the rod 18 as guides for the gasometer-cover other guides are dispensed with and the device is correspondingly simplified.

The device may be made by sheet-metal workers anywhere, and this, together with its simplicity and permanence, tends to put it readily within reach of users.

What I claim as new, and desire to secure by Letters Patent, is—

1. In a generator for acetylene gas, the combination of a generator-tank, a discharge-pipe in the tank terminating downward, an 115 automatically - rising water-can adapted to seal the discharge-pipe, a rod connected with the water-can and extended outside the tank, and a catch on the tank to hold the rod and the can in a lowered position, substantially 120 as set forth.

2. In a generator for acetylene gas, the combination of a generator-tank, a discharge-pipe in the tank terminating downward, a water-can adapted to seal the discharge-pipe, 125 a float to raise the water-can, a rod connected with the water-can and extended outside the tank, and a catch on the tank to hold the rod and the can in a lowered position, substantially as set forth.

3. In a generator for acetylene gas, the combination of a generator-tank having a dome raised above the general level of its cover, a discharge-pipe terminating down-

ward in the dome, a water-can adapted to seal the discharge-pipe, a float to raise the water-can, a rod connected with the water-can and extended outside the tank, and a catch on the tank to hold the rod and the can in a lowered position, substantially as set forth.

4. In a generator for acetylene gas, the combination of a generator-tank, a downward-discharging outlet-pipe having a downward-extended receiving end, a water-can under the receiving end of the discharge-pipe, a rod connecting with the water-can and extending outward and upward to one side of the cover of the generator-tank, a catch on the tank and a button on the rod adapted to engage the catch on the tank, substantially as set forth.

5. In a generator for acetylene gas, the

combination of a tank, a water-seal cover for the tank having an upward-projecting dome, an outlet-pipe extended upward into the dome 20 of the cover, and having a downward-extended receiving end, a water-can below the receiving end of the outlet-pipe, a rod connected with the water-can and extended outside the tank to one side of the cover, a lip on 25 the cover, a catch on the tank and a button on the rod adapted to engage the lip and the catch, substantially as set forth.

In testimony whereof I sign my name in the presence of two subscribing witnesses.

JOHN BOLAND.
